[57] CLAIM

The ornamental design for a pole mounted enclosure for base station, as shown and described.

DESCRIPTION

FIG. 1 is an isometric view from the front of a pole mounted enclosure for base station incorporating my design;

FIG. 2 is a isometric view showing the interior of the pole mounted enclosure for base station;

FIG. 3 is a front view thereof;

FIG. 4 is a left-side view thereof;

FIG. 5 is a right-side view thereof;

FIG. 6 is a top view thereof;

FIG. 7 is a bottom view thereof; and,

FIG. 8 is a back view thereof.

The pole has been shown broken away at both ends in FIGS. 1-8 to indicate indeterminate length.
